Inventor

Robert D. Cayce.

By Attorney

Patented Sept. 26, 1922.

UNITED STATES PATENT OFFICE.

ROBERT DYAS CAYCE, OF NASHVILLE, TENNESSEE.

MOISTENING DEVICE.

Application filed April 11, 1921. Serial No. 460,294.

To all whom it may concern:

Be it known that I, ROBERT D. CAYCE, a resident of Nashville, in the county of Davidson and State of Tennessee, a citizen 5 of the United States, have invented certain new and useful Improvements in Moistening Devices of which the following is a specification.

My invention relates to improvements in 10 moistening devices which, while capable of use in many situations, is particularly designed and constructed for use in connection with adding or other machines of this character where a moistening device would prove 15 a desirable adjunct for such a machine.

The main object of my invention is the provision of a device of the character and for the purpose stated which will preferably be mounted in the table or platform forming 20 the support for the machine, and which will be thus located to greatly assist the operator in performing his work.

Another object of my invention is the provision of a moistening device which will 25 form a part of the table or support of the adding or other machine, and which while performing services proving a great saving of time, labor and expense, will be capable of production at such a very small cost as to 30 make its use highly desirable and practical.

With these objects in view, the invention broadly stated, consists in the combination with a table or support for a machine, of a moistening device mounted in said table.

The invention further consists of a moistening device adapted for use in the table or support and embodying novel details of construction and arrangement of parts, substantially as shown, described and particularly 35 defined and distinguished by the claim.

In order that the construction and operation of my moistening device may be clearly understood and its many features of merit and numerous advantages be fully appreciated, I invite attention to the accompanying 40 drawing in which:

Figure 1 represents a perspective view showing the application and use of my moistening device to render its purpose entirely clear.

Fig. 2 represents a horizontal sectional view of the moistening device and table shown on an enlarged scale.

Fig. 3 represents a top plan view of the 55 novel moistening device embodying my improvement.

Fig. 4 represents a transverse sectional view of the table and moistening device, and

Fig. 5 represents a top plan view of one 60 corner of the table showing the opening in which the trough of my moistening device fits.

As before stated, the device is capable of service in various situations, but is particularly adapted for use in connection with the table or support 1 of the construction used for an adding machine 2, such table being provided at one corner with the inclined arranged opening 3, provided with a surrounding recess or channel 4, having at each end the notches or kerfs 5, and fitting in said channel and kerfs is the rim or flange 6, surrounding the trough 7, while said trough at each end is provided with recesses 75 8, forming bearings for the journals 9, of the moistening roller 10, said recesses 8 in the rim of the trough forming extensions 11, which fit in the said kerfs 5, thus attaching the trough with its moistening roller to the 80 table in the most convenient position, as shown in Fig. 1, to permit the operator to use one hand 12 for manipulation of the machine, and his other hand 13, for use upon the moistening device to greatly assist 85 him in rapidly handling the checks, drafts, or other instruments used in connection with the machine.

The advantages of my device will be instantly apparent and appreciated by all 90 persons skilled in the use of adding or like machines, and its trifling cost will make its use highly desirable and necessary for the purpose intended.

I claim:

In a device of the character described, the combination with a table for the machine and provided with a properly disposed opening, having a surrounding channel with a kerf at each end, of a trough having a surrounding rim fitting the channel around the opening of the table and flush with the surface of said table, and having at each end an offset forming a recess to fit in the kerfs of the channel around the opening of the table, and a moistening roller arranged in said trough with its journals bearing in the recesses of the rim of the trough and its surface projecting slightly above the table.

In testimony whereof I hereunto affix my 110 signature.

ROBERT DYAS CAYCE.
